Term of patent 14 years

(Cl. D44—1)

FIG. 1

FIG. 2

FIG. 3

FIG. 4

FIG. 5

FIG. 6

FIG. 7

FIG. 8

FIG. 1 is a top plan view of a cutting board showing my new design wherein the ends are slightly curved and the sides are parallel;

FIG. 2 is a bottom plan view of the cutting board;

FIG. 3 is a front elevational view of the cutting board;

FIG. 4 is a side elevational view of the cutting board;

FIG. 5 is a top plan view of another form of cutting board showing my new design wherein the ends are parallel and the sides are slightly curved;

FIG. 6 is a bottom plan view of the species of the cutting board shown in FIG. 5;

FIG. 7 is a front elevational view of the species of the cutting board shown in FIG. 5; and

FIG. 8 is a side elevational view of the species of the cutting board shown in FIG. 5.

The characteristic features of my design reside in the full line portions and comprise the provision on a cutting board having a pair of opposed parallel sides and a pair of opposed curved sides of end members and a field of contrasting colors, and further provision within the field on one face of the board of indicia of the same color as the end members.

I claim:

The ornamental design for a cutting board, substantially as shown and described.
